Filed Apr. 5, 1965, Ser. No. 84,606

Term of patent 14 years

(Cl. D61—1)

FIG. 1

FIG. 2

FIG. 3

FIG. 4

FIG. 5

FIG. 1 is a perspective view of a foldable light easel, showing my new design in erect or operative condition;

FIG. 2 is a perspective view thereof, on a reduced scale, showing the support panels removed and the easel folded, the switch being omitted for convenience of illustration;

FIG. 3 is a top plan view of the easel as seen in FIG. 1, again omitting the switch;

FIG. 4 is a side elevational view thereof, both sides being alike; and

FIG. 5 is a front elevational view of the easel as seen in FIG. 3, the rear being identical thereto.

I claim:

The ornamental design for a foldable light easel as shown and described.
